UNITED STATES PATENT OFFICE.

GRACE E. FAIRCHILD, OF NEW YORK, N. Y.

DESIGN FOR A BUTTON, EMBLEM, OR OTHER INSIGNIA.

50,884.

Specification for Design.

Patented June 5, 1917.

Application filed March 27, 1917. Serial No. 157,834. Term of patent 7 years.

To all whom it may concern:

Be it known that I, GRACE E. FAIRCHILD, a citizen of the United States, and resident of New York, in the county of New York and State of New York, have invented a new, original, and ornamental Design for Buttons, Emblems, or other Insignia, of which the following is a specification, reference being had therein to the accompanying drawing.

The single figure of the drawing is a plan view of a button or similar emblem showing my new design.

I claim:

The ornamental design for a button, emblem or other insignia as shown.

In testimony whereof I hereunto affix my signature.

GRACE E. FAIRCHILD.
